LOOM PICKER

Filed Jan. 29, 1941

UNITED STATES PATENT OFFICE

2,325,187

LOOM PICKER

Arthur P. Lewis, Fairhaven, Mass.

Application January 29, 1941, Serial No. 376,437

13 Claims. (Cl. 139—159)

This invention relates to loom pickers and is more especially concerned with the construction of the block or "lug" which is mounted on the picker stick and forms the element through which the motion of the picker stick is transmitted to the shuttle. In addition, it is also the member which initially receives the blow of the shuttle as it comes into the shuttle box, one of its functions being to cooperate with the walls of the shuttle box in stopping the shuttle at the end of its flight.

Because of the nature of the service required of articles of this type they depreciate rapidly and it is therefore necessary to renew them at frequent intervals.

The present invention deals with this situation and it aims to improve loom pickers with a view to materially increasing their serviceable life, while at the same time producing an article having the characteristics desired in practice and providing a construction which can be manufactured economically.

The nature of the invention will be readily understood from the following description when read in connection with the accompanying drawing, and the novel features will be particularly pointed out in the appended claims.

In the drawing,

Figure 1 is a perspective view of a picker constructed in accordance with this invention;

Fig. 2 is a side view showing one step in the process of manufacture of the picker shown in Fig. 1;

Fig. 3 is a sectional view approximately on the line 3—3, Fig. 2;

Fig. 4 is a side view showing additional steps in the process of manufacture;

Fig. 5 is a vertical, sectional view of the picker after the assembling operations on it have been performed and it is ready to be molded;

Fig. 6 is a sectional view approximately on the line 6—6, Fig. 1; and

Figs. 7 and 8 are plan views showing fabric pieces used in building up the picker shown in the other figures.

Referring first to Fig. 1, the picker there shown comprises a loop section 2 designed to encircle the picker stick 3, and a block or pad section 4 which, when the device is in its operative position, is located at the forward side of the picker stick in position to engage the shuttle in propelling it, and to be engaged by it in stopping the latter.

In manufacturing this picker according to the process provided by this invention, the loop section 2 is initially formed by winding a strip of

rubber impregnated woven fabric around a mandrel of substantially the shape and dimensions of a picker stick. The strip preferably is cut parallel to the warp or filling threads. This winding operation may be performed by hand, or in any convenient manner. It should be noted, however, that because of the manner in which parts of the pad 4 are to be secured to and interlocked with the loop section 2, the latter section is not wound on the mandrel alone but, preparatory to that operation, a series of strips 5 of fabric which are to form a part of the pad are placed against the front face of the picker stick, or the mandrel corresponding to it, and the fabric from 10 which the section 2 is made is wound around both the mandrel and the intermediate or reduced sections 5', Fig. 8, of the strips 5. If desired, however, this winding operation may be performed on a mandrel sufficiently larger than 20 the picker stick to produce a closed loop of the same dimensions that would be made by the procedure above set forth.

At an intermediate point in this winding operation a pad 6, Figs. 3, 5 and 6, of rubber, or any equivalent resilient material, may be placed between certain of the plies where it will aid in resisting destructive action of the holding screw usually inserted through this part of the loop section.

20 The fabric strips 5 preferably are cut on the bias for reasons hereinafter explained, and additional fabric pieces 7 of the shape shown in Fig. 7 also are cut from the same or some other suitable textile fabric. While a considerable variety of fabrics can be conveniently used in the manufacture of this picker, I have found that those in the nature of Osnaburg, the coarser sheetings, or even a light grade of duck are suitable for this purpose. Preferably they are impregnated with rubber either by a dipping operation or calendar coating prior to cutting out the parts 5 and 7 or splitting the web into the strips used in winding the section 2. Three or four pieces 7 of this rubber impregnated material are 30 placed one upon the other to form a filler piece or section 7' which is placed against the forward side of the wound section 2, as best shown in Figs. 2 and 3, and the lower ends of these pieces 7 are curved around the lower edge of the section 2 at its forward end, as best shown in Figs. 2 and 5. At this time the surfaces of the fabric pieces are sufficiently tacky to adhere firmly to each other.

Next the ends of the outermost strip 5 are 35 folded alternately up and down across the front

face of the section 1' and the surplus material is cut off. Or, the first two strips of each set may be folded over together, as shown in Fig. 4, but thereafter it is preferable to fold the upper ones down and the lower ones up individually and alternately, these operations being continued with each of the strips until all of them have been so folded into place. The ends of those folded upwardly are cut off flush with the upper surface of the body as it is built up, while those folded downwardly are cut off to such a length that they will approximately meet the front face of the foremost of the remaining strips of the lower set. At the completion of this operation the assembled body will appear about as shown in Fig. 5.

Next the body so built up is placed in a suitable mold where, with the aid of heat and pressure, it is molded into its final form, as shown in Fig. 1, and the rubber binding material with which the plies are impregnated is vulcanized or cured to the desired degree. During this molding and vulcanizing operation the rounded projection *a*, Fig. 1, is formed at the lower side of the pad or block 4, and the tapered hole *b* to receive the point of the shuttle also is formed, the edges and corners are rounded, where desired, and the surfaces are made hard and smooth. If rubber additional to that carried by the fabric plies is required for this purpose it can readily be introduced. Usually, however, this is not necessary.

In this connection it may be pointed out that the picker must be finished to three fixed dimensions in order to function properly in a given loom with a certain picker stick, shuttle, and box clearances. Consequently, the number of plies used in making up the sections of the picker, as above described, while subject to much variation to suit the requirements of different looms, must be so predetermined that after the body has been molded to the desired form, the finished article will have the necessary dimensions.

It should be observed that in the completed article the fabric plies 5 of the pad are mechanically interlocked with the loop section 2 by virtue of the fact that they encircle the latter section at its forward end. The plies 5 also bind the intermediate filler section 1' firmly in place against the forward end face of the loop 2 and against the lower forward edge thereof, and an especially secure union of all of these parts is provided by the interleaving of the overlapped ends of the strips 5 at the forward face of the filler section. This mechanical arrangement of the plies cooperates with the adhesion of the rubbery impregnating medium in binding the parts of the entire body together into a solid integral structure.

The bias cutting of the fabric pieces 5 and 7 is of advantage in producing a pad section 4 which will better resist the disintegrating engagement of this member with the metal end of the shuttle. It will be evident from an inspection of Fig. 1 that as the diameter of the hole *b* increases, due to wear, and finally begins to break through at the sides of the pad 4, the warp and filling threads still resisting such breakage have long lengths anchored securely in the body of the block. On the other hand, if these warp or filling threads were parallel to the edges of the block, the horizontal threads would offer less and less resistance to the spreading action on the block as the edges of the hole *b* approached the vertical edges of the block. Practically all

of this resistance ultimately would come on the vertical threads which are not so disposed as to effectually resist such action. The diagonal cutting, however, so disposes both sets of threads that they are diagonally related to the lateral faces of the block and thus both the warp and filling are more favorably positioned to resist those forces tending to spread the block.

Pickers made in accordance with this invention have proved in actual practice to give an exceptionally high period of serviceability. At the same time the expense of manufacturing them, while slightly higher than prior art constructions of a similar type, is within entirely reasonable limits.

While I have herein shown and described a preferred embodiment of my invention, it will be evident that the invention may be embodied in other forms without departing from the spirit or scope thereof.

Having thus described my invention, what I desire to claim as new is:

1. A loom picker comprising a loop section adapted to encircle a picker stick, a pad section adapted to be positioned at the forward side of the stick and comprising strips of fabric extending through the aperture in said loop section at the forward portion thereof, a non-metallic filler piece at the outer and forward side of said loop section, the ends of said strips being folded over said filler piece and overlapped one upon the other at the forward side of said piece, and a binder uniting said plies, said filler piece, and said sections into an integral structure.

2. A loom picker comprising a section adapted to encircle a picker stick, a pad section composed chiefly of plies of bias cut woven fabric with the threads thereof disposed angularly to the sides of the pad section, and a binder uniting said plies and said sections into an integral structure.

3. A loom picker comprising a section adapted to encircle a picker stick and including a strip of fabric wound into the form of a closed loop, a laminated pad section comprising lengths of fabric superposed one on the other and folded around a portion of said loop section at the end thereof designed to be positioned at the forward side of the stick, the laminations of the pad section all extending transversely of the pad section, and a binding material uniting said plies and said sections into an integral structure.

4. A loom picker comprising a section adapted to encircle a picker stick and including a strip of fabric wound into the form of a closed loop, and a pad section encircling a portion of said loop section at the forward end of the latter and comprising a series of superposed transversely extended layers of fabric, and a binder uniting said layers of fabric and said sections into an integral structure.

5. A loom picker comprising a section adapted to encircle a picker stick and including a strip of fabric wound into the form of a closed loop, a pad section comprising lengths of bias cut woven fabric extending through the aperture in said first section and covering portions of the latter section at both the inner and outer sides thereof, the wearing portion of the pad section being made up of transversely extended layers, and a binding material uniting said lengths of fabric and said sections into an integral structure.

6. A loom picker comprising a section adapted to encircle a picker stick and including a strip

of fabric wound into the form of a closed loop, a filler section including superposed plies of fabric placed one upon the other and positioned at the forward and outer side of said loop section, and a series of bias cut lengths of woven fabric extending through the aperture in said loop section and across the front face of said filler section, the wearing portion of the pad section being made up of transversely extended layers, and a binding material uniting said fabric sections into an integral structure.

7. A loom picker according to preceding claim 3, including a rubber pad interposed between the plies of said loop section at the end thereof opposite to said pad section.

8. A loom picker comprising a strip of fabric wound into the form of a closed loop adapted to encircle a picker stick, strips of bias cut woven fabric extending through the aperture in said loop section and folded over the outer face of the latter at the forward end thereof, a filler section interposed between the forward side of said loop section and the folded over portions of said bias cut strips, and a flexible binding material uniting all of said fabric sections into an integral structure.

9. A loom picker comprising a loop section adapted to encircle a picker stick, a pad section adapted to be positioned at the forward side of the stick and comprising layers of fabric folded around a portion of said loop section with both the warp and weft threads thereof disposed at a substantial angle to the plane of the side of the picker, and a binder uniting the plies of said sections and joining said sections together into an integral structure.

10. A loom picker comprising a loop section adapted to encircle a picker stick, a pad section adapted to be positioned at the forward side of the stick and comprising strips of fabric extending through the aperture in said loop section at the forward portion thereof and folded over the forward side of the loop section with both the warp and weft threads thereof disposed at a substantial angle to the plane of the side of the picker, and a binder uniting said plies and said sections into an integral structure.
11. A loom picker comprising a loop section adapted to encircle a picker stick, a pad section adapted to be positioned at the forward side of the stick and comprising strips of fabric extending through the aperture into said loop section at the forward portion thereof and folded over each other in interleaved relationship at the forward side of said loop section with both the warp and weft threads thereof disposed at a substantial angle to the plane of the side of the picker, and a binder uniting said plies and said sections into an integral structure.
12. A loom picker comprising a strip of fabric wound into the form of a closed loop and encircling a picker stick, a pad section composed chiefly of plies of bias cut woven fabric each having a portion extending through said loop to be secured thereto at the forward edge of the picker stick, the shuttle engaging portion of the pad section being made up of layers extending transversely of the picker stick, and binding material uniting all of said fabric sections into an integral structure.
